UNITED STATES PATENT OFFICE.

CHARLES GRIFFITH ROBINSON, OF BUFFALO, NEW YORK, ASSIGNOR TO THE BEAVER COMPANY, A CORPORATION OF OHIO.

WEATHERBOARD.

Application filed January 12, 1920. Serial No. 350,793.

To all whom it may concern:

Be it known that I, CHARLES GRIFFITH ROBINSON, a citizen of the United States, residing at Buffalo, in the county of Erie, State 5 of New York, have invented certain new and useful Improvements in Weatherboard (Case C); and I do hereby declare the following to be a full, clear, and exact description of the invention, such as will enable 10 others skilled in the art to which it appertains to make and use the same.

This invention relates to weather board for use in building, and more especially to weather board or siding of the so-called 15 wood brick veneer type. The invention has for its object the provision of an improved weather board of this character. More particularly, the invention contemplates the provision of an improved construction for effecting a weather-tight joint between the 20 longitudinal edges of adjacent boards when assembled on the frame of a building.

Weather board is used in large quantities on the side of buildings where it is nailed, or 25 otherwise appropriately secured, to the frame of the building to form the exterior thereof. In order to present a pleasing appearance, such weather board should be of an artistic design, and to this end the 30 weather board is frequently formed so as to present the appearance of a brick wall when assembled and secured to the frame of the building. Weather board for producing this brick effect is generally known in the trade 35 as "wood brick veneer", and some times as "imitation brick weather boarding", and it is to this type of weather board that the present invention particularly relates.

Weather board is ordinarily marketed in 40 the form of board lengths, usually of about the width of ordinary building bricks, for example, about three or four inches in width. The longitudinal edges of these boards are formed with complementary tongues, 45 grooves, or the like, for providing a weather-tight joint between adjacent boards when assembled and secured to the frame of the building. Various forms of joints for this purpose have heretofore been employed in 50 the manufacture of weather board. The present invention contemplates the provision of an improved joint for the purposes aforesaid, and in its broad aspect involves the provision of a board having a longitudinal 55 groove extending to one edge of the board

with a longitudinally extending slot in the other portion of this edge of the board and having in its opposite edge a longitudinally extending rib or tongue complementary to the slot in the other edge of the board. 60

In carrying out the invention, I form on the face of the board, and extending to one edge thereof, a longitudinal square-cornered groove of a depth approximately one-third of the thickness of the board. In this same 65 edge of the board I form a slot parallel to the afore-mentioned groove. On the opposite longitudinal edge of the board I provide a rib or tongue complementary to the slot in the other edge. In defining the configurations of the opposite longitudinal edges of the board as complementary, I mean that when the boards are properly assembled, the edge of one board will fit into or complete 70 the contacting edge of the next adjacent 75 board, thereby providing a satisfactory joint between adjacent boards as well as providing a more or less unitary structure of the assembled boards.

The novel features of the invention which 80 I believe to be patentable are definitely indicated in the appended claims. These features, together with the structure of weather board embodying the same, will be clearly understood from the following description, 85 taken in conjunction with the accompanying drawings, in which:

Fig. 1 is a perspective view of the improved weather board of the invention assembled as the corner of a building; 90

Fig. 2 is a sectional view taken on the section line 2—2 of Fig. 1;

Fig. 3 is a plan of a portion of the weather board illustrated in Fig. 2;

Figs. 4 and 5 are plan and end views, respectively, of a weather board embodying the improved joint of the invention and of a width of corresponding to the width of ordinary building brick; 95

Fig. 6 is an end view of a weather board 100 having a slightly modified form of joint embodying the principles of the invention; and

Figs. 7 and 8 are enlarged views of the joints of the boards shown in Figs. 5 and 6, respectively. 105

Referring first to Figs. 2 and 3 of the drawings, it will be observed that the weather board therein illustrated presents on its face the appearance of three rows of laid brick. This appearance is imparted to 110

the board by forming on its face three longitudinal square-cornered grooves 10 extending the entire length of the board. The grooves 10 are appropriately spaced, so that the raised portions between adjacent pairs of the grooves approximate in width the width of ordinary building brick. The grooves 10 are, of course, parallel, and are of such depth as to present, when the boards 10 are assembled, the appearance of a brick wall with rake joints.

A series of transverse square-cornered grooves 11 is formed between each adjacent pair of longitudinal grooves 10. The grooves 15 in each series of the transverse grooves 11 are out of alignment with the grooves in any adjacent series of the transverse grooves. The transverse grooves 11 are of the same depth as the longitudinal grooves 10, and in 20 each series of transverse grooves the individual grooves of the series are appropriately spaced so that the raised portions on the face of the board present the appearance of a plurality of layers of laid brick. 25 The longitudinal edges of the board are fashioned, in accordance with the present invention, so as to form an improved weather-tight joint between contacting edges of the boards when assembled in position in 30 building. Thus, in accordance with the invention, a portion 16 of one of the longitudinal edges of the board lies in a plane at right angles to the face of the board. In depth, this portion 16 corresponds to the 35 depth of the groove 10 and extends from the face of the board inwardly. The other portion of this edge of the board is inclined as indicated by reference character 13 in the drawings and a rib or tongue 14 is formed 40 in about the middle of the inclined portion 13. The other edge of the board has in its face a longitudinal groove 10 extending to the edge of the board, and the remainder of this edge is inclined as indicated by reference 45 character 12 in the drawings and is moreover provided with a slot 15. The inclined portions 12 and 13 and the rib 14 and slot 15 are complementary and when the boards are assembled the inclined portions 50 contact with one another and the rib 14 fits into the slot 15 and the groove 10 at the edge of the board presents the same appearance as the intermediate grooves 10 in the main body face of the board.

55 The portion of the wall represented in Fig. 1 of the drawings is two boards high, with respect to the width of board represented in Figs. 2 and 3 of the drawings. With respect to the board represented in 60 Fig. 5 of the drawings, the wall of Fig. 1 is six boards high. It will be evident that the wider board illustrated in Figs. 2 and 3 of the drawings may be more economically assembled, and for this reason I generally prefer to form the improved board of the

invention of a width corresponding to a plurality of layers of laid brick. In my application Serial No. 350,817, filed January 9, 1920, I have claimed a weather board having on its face a plurality of spaced longitudinal grooves and a plurality of spaced transverse grooves, whereby the face of the board presents the appearance of a plurality of rows of laid brick. 70

In Figs. 6 and 8 of the drawings, a slightly modified form of joint embodying the invention is illustrated. In this modification of the invention a slot 17 is formed in that edge of the board in which the groove 10 extends to the edge, the slot 17 being intermediate the bottom of the groove 10 and the back of the board. The remaining surface of this edge of the board is squared with respect to the face and back of the board. The opposite edge of the board is squared, 85 with respect to the face and back thereof, except for an intermediate rib or tongue 18 which is complementary to the slot 17 in the other edge of the board.

The improved joint of the invention is a 90 convenient one for assembling and provides a satisfactory weather-tight joint. One side of the longitudinal groove 10 extending to the edge of the board is completed by the squared portion of the contacting edge of 95 the next adjacent board, so that the longitudinal groove at the edge of the board thereby has the appearance of a rake joint in a brick wall.

Preferably the cheaper forms of lumber, 100 such, for example, as hard or soft pine, are generally used in the manufacture of weather board, since lumber of this character is ordinarily satisfactory for the siding of frame buildings. The face of the board 105 need not be planed or smooth, and in fact it is preferable that the face be slightly roughened, since in this condition it more nearly simulates the surface of building brick, and, moreover, is better adapted for 110 the reception of paint or similar decorative agents. For this reason, it is satisfactory to leave the face of the board in its rough-sawed condition. When assembled, the raised portions on the face of the board may 115 be painted an appropriate color, usually red, to simulate the color of red building brick, while both the longitudinal and transverse grooves may be painted a different color, for example, black, so that the finished exterior of the building presents the appearance of a brick wall with rake joints. 120

I claim:

1. A weather board having a longitudinal groove in the face thereof extending to one 125 of the longitudinal edges of the board, an adjacent longitudinal groove, transverse grooves extending between said longitudinal grooves to give the appearance of a row of laid brick, said edge of the board being in- 130

clined and having a longitudinally extending slot intermediate the bottom of said groove and the back of the board, the opposite edge of the board having a square portion and 5 having inclined portions with a tongue intermediate said inclined portions, said tongue and said inclined portions being complementary to the inclined portions and intermediate slot of the other edge of the board, 10 substantially as described.

2. A weather board having a square cornered longitudinal groove in the face thereof extending to one of the longitudinal edges of the board, an adjacent square 15 cornered longitudinal groove and transverse square cornered grooves extending

between said longitudinal grooves, said edge of the board being inclined and having a longitudinally extending slot intermediate the bottom of said groove and the 20 back of the board, the opposite edge of the board having a squared portion of substantially the same depth as the depth of said first mentioned groove and having inclined portions and a tongue intermediate 25 said portions, said tongue and said inclined portions being complementary to the inclined portions and intermediate slot of the other edge of the board.

In testimony whereof I affix my signature.

CHARLES GRIFFITH ROBINSON.
